UNITED STATES PATENT OFFICE

172,469

COMBINED TOILET SEAT, COVER, AND VENTILATING DEVICE

William Gudish, Los Angeles, Calif.

Application April 29, 1953, Serial No. 24,752

Term of patent 14 years

(Cl. D4—5)

To all whom it may concern:

Be it known that I, William Gudish, a citizen of the United States and resident of Los Angeles, in the county of Los Angeles and State of California, have invented a new, original, and ornamental design for a Combined Toilet Seat, Cover, and Ventilating Device, of which the following is a specification, reference being had to the accompanying drawing, forming a part thereof.

Figure 1 is a perspective view of a combined toilet seat, cover, and ventilating device showing my new design;

Figure 2 is a fragmentary side elevational view;

Figure 3 is a top fragmentary view;

Figure 4 is a fragmentary elevational view taken from the side opposite to that shown in Figure 2; and

Figure 5 is a fragmentary bottom view.

The dominant features of my new design are shown in the drawing in solid lines.

I claim:

The ornamental design for a combined toilet seat, cover, and ventilating device, substantially as shown and described.
